UNITED STATES PATENT OFFICE.

PERCY DOUGALL, OF KIDDERMINSTER, ENGLAND.

INTERNAL-COMBUSTION ENGINE.

1,423,407.

Specification of Letters Patent. Patented July 18, 1922.

Application filed August 27, 1920. Serial No. 406,267.

To all whom it may concern:

Be it known that I, PERCY DOUGALL, subject of the King of Great Britain, residing at Kidderminster, England, have invented 5 certain new and useful Improvements in Internal-Combustion Engines, of which the following is a specification.

This invention relates to gas engines and other internal combustion engines having 10 separate air and gas valves of that type which are governed by the "hit-and-miss" or similar method, intermittent idle strokes occurring due to the gas valve not opening during certain of the suction strokes, above 15 a predetermined speed.

The object of the present invention is to prevent the loss of power involved by the compression of the air in the cylinder during the inward strokes preceding the said idle 20 strokes, thereby increasing the efficiency of the engine.

According to the invention, a valve in the cylinder (which may be the existing inlet or exhaust valve or an independent valve) 25 is controlled by the governor, so as to open during the inward strokes preceding the idle outward strokes in order to discharge into the atmosphere the air which is displaced by the piston, without the said air 30 being compressed as usual, thus avoiding the useless absorption of power from the engine.

Figure 1 of the accompanying drawings show a sectional elevation of an arrangement 35 constructed in accordance with this invention, for admitting of the release of the air drawn into the cylinder preceding the idle strokes of the piston, the air release valve being shown closed.

Figure 2 is a sectional elevation of the arrangement, showing the air release valve open.

Figure 3 shows more clearly, upon a larger scale, the manner in which the gas valve 45 and air release valve are controlled by the governor.

The same reference numerals indicate corresponding parts in each of the figures.

Referring to the drawings, the gas valve is 50 operated by means of a cam 1 geared up with the crank shaft of the engine, the said cam 1 as usual, being arranged to engage with the arm of a pecker 2 so that the latter is moved forward and engages with a pecker-block 3 normally disposed between the pecker 55 3 and the valve stem 4, the valve being thus

lifted and the gas port opened. The pecker-block 3 is carried by a depending arm 5 fixed to the end of one arm 6 of a bell-crank lever pivoted at 7 to a fixed support, the said arm 6 of the lever being connected up with the governor 8 in such a manner that when the speed of the engine becomes excessive the governor 8 raises the said arm 5 upwards and moves the pecker-block 3 out of engagement with the pecker 2, so that a miss takes place, the gas valve remaining closed. To prevent the air which has been drawn into the cylinder through the suction operated valve 22 on the last suction stroke from being compressed during the inward strokes preceding idle strokes of the latter and thus resulting in a loss in the efficiency of the engine, an air-release valve 9 is provided which automatically opens when the gas 75 supply is cut off. This air release valve 9 is carried by one end of a lever 10 pivoted at about the middle at 11 the opposite end of the lever carrying a tappet-rod 12 working within suitable guides 13. Arranged directly opposite to the end of the tappet-rod 12 is an operating rod 14 working within guides 15 and pivoted to one end of a lever member 16 whose opposite end is engaged by the cam 1 operating the gas valve. The 85 other arm 17 of the bell crank lever which actuates the pecker-block 3 carries an intermediate member 18 which is adapted to be interposed between the operating rod 14 and the tappet-rod 12 so that the said operating 90 rod engages with the latter through the medium of the intermediate member 18 which results in the air release valve being lifted. The said intermediate member 18 is preferably slotted longitudinally at 19, the 95 slot being engaged by the square end of a rod 20 jointed at its opposite end to the arm 17 of the bell crank lever, the rod 20 being supported by and free to move longitudinally within a guide 21, as shown in Figure 100 3 of the drawings.

When the speed becomes excessive and the arm 6 of the bell crank lever carrying the pecker block 3 is raised by the governor 8 so that a miss takes place and the gas port is 105 closed, the other arm 17 of the bell crank lever is at the same time moved outwards, as shown in Figure 2, and the intermediate member 18 carried by the said arm is interposed between the tappet-rod 12 and the 110 operating rod 14 of the air release valve 9, the latter being thus operated by the cam 1

so as to allow the air in the cylinder to escape into the atmosphere. On the engine speed decreasing the intermediate member 18 is moved out of engagement with the tappet-rod 12 of the air valve 9, as shown in Figure 1, so that the air valve is not opened, whilst the pecker-block 3 carried by the opposite arm 6 of the bell crank lever is again engaged with the pecker 2 so that the gas valve is raised by the cam 1.

Instead of a special air-release valve being employed the exhaust valve may serve a similar purpose being operated from the bell crank lever in a similar manner.

Having fully described my invention, what I desire to claim and secure by Letters Patent is:—

1. In an internal combustion engine, the combination with the cylinder, of separate air and gas intake valves, a governor controlling the gas valve so as to cause the latter to remain closed at excessive speed, an air-release valve in the cylinder, a cam for operating said air-release valve, and a displaceable intermediate member adapted to complete the operative connection between the cam and air-release valve, said displaceable member being connected to the governor so as automatically to break the connection be-

tween the cam and air valve when the gas valve is operative and to establish the said connection when the gas valve is inoperative.

2. In an internal combustion engine, the combination with the cylinder, of a gas valve, a displaceable pecker block for operating said gas valve, a lever connected to the pecker block, a governor influencing the lever and pecker-block so as to render the gas valve inoperative at high speeds, an air-release valve in the cylinder, a cam for operating said air-release valve, and a displaceable intermediate member adapted to complete the operative connection between the cam and air-release valve, said displaceable member being connected to the governor-influenced lever so as automatically to break the connection between the cam and air-release valve when the gas valve is operative, and to establish the said connection when the gas valve is inoperative.

In testimony whereof I have hereunto set my hand in presence of two subscribing witnesses.

PERCY DOUGALL.
